(57) **CLAIM**

The ornamental design for furniture having support legs and a support surface, as shown and described.

DESCRIPTION

FIG. 1 is a top three-quarters perspective view of a first embodiment of a design for furniture having support legs and a support surface.

FIG. 2 is a bottom three-quarters perspective view of the first embodiment of a design for furniture having support legs and a support surface.

FIG. 3 is a bottom view of the first embodiment of a design for furniture having support legs and a support surface.

FIG. 4 is a top view of the first embodiment of a design for furniture having support legs and a support surface.

FIG. 5 is a front side view of the first embodiment of a design for furniture having support legs and a support surface.

FIG. 6 is a back side view of the first embodiment of a design for furniture having support legs and a support surface.

FIG. 7 is a right side view of the first embodiment of a design for furniture having support legs and a support surface.

FIG. 8 is a left side view of the first embodiment of a design for furniture having support legs and a support surface.

FIG. 9 is a top three-quarters perspective view of a second embodiment of a design for furniture having support legs and a support surface.

FIG. 10 is a bottom three-quarters perspective view of the second embodiment of a design for furniture having support legs and a support surface.

FIG. 11 is a bottom view of the second embodiment of a design for furniture having support legs and a support surface.

FIG. 12 is a top view of the second embodiment of a design for furniture having support legs and a support surface.

FIG. 13 is a front side view of the second embodiment of a design for furniture having support legs and a support surface.

FIG. 14 is a back side view of the second embodiment of a design for furniture having support legs and a support surface.

FIG. 15 is a right side view of the second embodiment of a design for furniture having support legs and a support surface.

FIG. 16 is a left side view of the second embodiment of a design for furniture having support legs and a support surface.

FIG. 17 is a bottom three-quarters perspective view of a third embodiment of a design for furniture having support legs and a support surface.

FIG. 18 is a top three-quarters perspective view of the third embodiment of a design for furniture having support legs and a support surface.

FIG. 19 is a bottom view of the third embodiment of a design for furniture having support legs and a support surface.

FIG. 20 is a top view of the third embodiment of a design for furniture having support legs and a support surface.

FIG. 21 is a front side view of the third embodiment of a design for furniture having support legs and a support surface.

FIG. 22 is a back side view of the third embodiment of a design for furniture having support legs and a support surface.

FIG. 23 is a bottom three-quarters perspective view of a fourth embodiment of a design for furniture having support legs and a support surface.

FIG. 24 is a top three-quarters perspective view of the fourth embodiment of a design for furniture having support legs and a support surface.

FIG. 25 is a bottom view of the fourth embodiment of a design for furniture having support legs and a support surface.

FIG. 26 is a top view of the fourth embodiment of a design for furniture having support legs and a support surface.

FIG. 27 is a front side view of the fourth embodiment of a design for furniture having support legs and a support surface.

FIG. 28 is a back side view of the fourth embodiment of a design for furniture having support legs and a support surface.

FIG. 29 is a right side view of the fourth embodiment of a design for furniture having support legs and a support surface; and,

FIG. 30 is a left side view of the fourth embodiment of a design for furniture having support legs and a support surface.
